UNITED STATES PATENT OFFICE

109,411

DESIGN FOR A BICYCLE

James S. Manton, Oak Park, Ill.

Application January 15, 1937, Serial No. 67,069

Term of patent 14 years

To all whom it may concern:

Be it known that I, James S. Manton, a citizen of the United States, residing at Oak Park, in the county of Cook and State of Illinois, have invented a new, original, and ornamental Design for a Bicycle, of which the following is a specification, reference being had to the accompanying drawing, forming a part thereof.

Figure 1 is a side elevational view of a bicycle showing my new design; and

Figure 2 is a front elevational view of the bicycle shown in Figure 1.

The substantially horizontally disposed plate

connected to the bicycle head and having truss rod receiving portions formed integrally with and disposed in the plane thereof, together with the truss rods extending upwardly above the bicycle head forwardly thereof and then curved downwardly to enter the rod receiving portions of said plate from the upper surface thereof, constitutes the dominant feature of my present design.

I claim:

The ornamental design for a bicycle, as shown and described.

JAMES S. MANTON.
